UNITED STATES PATENT OFFICE

VICTOR R. HEFTLER, OF DETROIT, MICHIGAN, ASSIGNOR TO SOCIETE DU CARBURATEUR ZENITH, OF LYON, FRANCE, A CORPORATION OF FRANCE

CARBURETOR

Application filed October 26, 1922. Serial No. 597,032.

The present invention relates to carburetors of the type adapted for use with internal combustion engines, and more particularly to improved structural features whereby the manufacture and assembly of the carburetor is facilitated and improved operating results are obtained.

In the accompanying drawings there is shown, for purposes of illustration only, a preferred embodiment of this invention, it being understood that the drawings do not define the limits of the invention as changes may obviously be made in the construction and operation disclosed without departing 15 from the spirit or scope of my broader claims.

In these drawings,—

Figure 1 is a vertical sectional view through a carburetor constructed in accordance with the present invention;

Figure 2 is a detail sectional view, on an enlarged scale, of a portion of the fuel feeding means associated with the atmospheric well;

Figure 3 is a detail sectional view on an enlarged scale, illustrating an improved fuel feeding means; and

Figure 4 is a detail sectional view of a modified form of fuel feeding means.

In carrying out the present invention, there is preferably provided a main body member 2 in the form of a casting. This member may be, if desired, constructed of a corrodible metal, such as cast iron, whereby the cost of the construction is greatly reduced. Extending through the casting is the usual air inlet passage 3 which may be provided with an auxiliary air inlet control 4 of the type shown in my Patent No. 1,418,259, of May 30, 1922, and with a choke valve 5.

Extending through the wall of the body member 2 is a set screw 6 adapted to engage an opening in the casing 7 of a composite venturi member. This venturi, while it may be of any well known construction, is preferably of the type illustrated in the copending application of Henri de Bolschevalier, Serial No. 595,878, filed Oct. 20, 1922, which resulted in Patent No. 567,043, patented Dec.

29, 1925. This forms a suitable mixing chamber, the outlet from which may be controlled by a throttle valve 8, as is customary in the art.

Projecting laterally from one side of the member 2 is a shelf 9 provided with an opening adapted to receive a stem 10. This stem is preferably formed with an upper shoulder 11 and is provided with an intermediate threaded portion 12 adapted to cooperate with a nut 13. After the stem is slipped in position through the opening in the shelf 9, there is placed over the lower end thereof a supplemental cover 14 having a depending flange 15. This cover, after it is placed in position, is clamped against the lower surface of the shelf by the nut 13.

The upper end of the stem 10 may be internally threaded to receive a screw 16, by means of which the gasoline inlet 17 may be adjustably clamped in position. Surrounding the upper end of the stem 10 and enclosed within the casing formed by the gasoline inlet, is a filter 18 adapted to remove any foreign particles from the fuel before its passage into the longitudinally extending opening 19 in the stem. This construction permits the gasoline inlet to be readily adjusted as required in installing the carburetor and also makes the filter readily accessible for cleaning and inspection.

Intermediate its length, and at substantially the point of intersection of the median horizontal and vertical planes extending through the float chamber, is a seat 20 for a needle valve 21 longitudinally movable in the lower end of the stem. This needle valve is adapted to be directly operated by a float 22 surrounding the stem and provided with a central cup shaped member 23, the bottom of which engages the lower end of the needle valve. By reason of this construction, it will be apparent that as the float rises it will directly operate the needle valve to cut off the supply of gasoline, while as it lowers the reverse operation will take place.

The main body of the float chamber may comprise a suitable stamping 24 adapted to be clamped in position on a base member 25 by means of a hollow screw 26. The base

member, as disclosed in my copending application hereinbefore referred to, is preferably composed of non-corrodible metal, such as brass, whereby the action of the gasoline thereon and of the water contained in the gasoline supply does not tend to corrode or otherwise clog the fuel openings. This base member may be secured to the main body member in any desired manner whereby it may be easily removed, as will be apparent. The float chamber preferably has a cover 27 carried by the stamping 24 and adapted to be enclosed within the supplemental cover 14 when the parts are in assembled position.

15 The idea broadly of constructing a carburetor of a main body portion having a projecting shelf and a separable base portion, and clamping the float chamber in position between the shelf and the base, is made the 20 subject matter of my copending application Serial No. 570,117, filed June 22, 1922. In said application, however, the construction is such that the atmospheric well is positioned outside of the air passage.

25 These advantages are obtained by providing within the base member 25 a main feed channel 28 adapted to feed the atmospheric well 29 and the main nozzle 30. The atmospheric well 29 is located entirely within the 30 main body portion 2 of the carburetor and is adapted to supply fuel to a quill 31 delivering fuel for slow speed and starting purposes through a nozzle 32. The amount of fuel in proportion to the air may be controlled 35 by a needle valve 33, as clearly shown in Figure 2. For facilitating assembly, the upper end of the quill 31 may have a driven fit with a sleeve 34, which sleeve may be held in position by a bent clip 35. The atmospheric well 40 may be open to the atmosphere through suitably arranged openings 36.

Formed in the base member 25 and extending from the atmospheric well to a point adjacent the main nozzle 30, is a channel 37 45 adapted to feed fuel from the atmospheric well to the cap nozzle 38. When the fuel in the atmospheric well has been exhausted, which occurs at a time comparatively early in the operation of the carburetor, a mixture of 50 air and gasoline will thereafter be supplied to the cap jet.

In order to obtain the advantages of the flow through an opening in a relatively thin member, as disclosed, for example, in my 55 Patent No. 1,255,165, of February 5, 1918, the body portion of both the atmospheric well and the main nozzle is formed adjacent the lower end with an inwardly projecting shoulder 39 and a peripheral flange 40. During the manufacture of the parts, disks 41 are placed against the shoulders 39 and within the peripheral flanges, and the flanges are then turned inwardly to tightly clamp the disks in position. With this construction 60 it is unnecessary to provide a separate pe-

ripheral envelope for enclosing the disks, and the assembly of the carburetor is greatly facilitated. At the same time, this construction prevents leakage of gasoline around the disks, thereby necessitating a determinate flow 70 through the calibrated openings provided in the disks for that purpose.

In some cases it has been found that a flat disk has a tendency to buckle, thereby changing the flow characteristics of the calibrated 75 orifice. This may be easily overcome by the modified construction illustrated in Figure 4. In this form, the calibrated opening 42 is formed in the disk shaped portion of a cup-shaped blank 43. By known apparatus, such as a compound die, the cups may be simultaneously cut from a body of metal, drawn, and pierced. This cup may then be secured, as by soldering, within a suitable holder 43'. In this construction there is an inwardly projecting shoulder 44 and a peripheral flange 45, there being a fuel feeding passage 46 through the body of the holder.

The advantages of the present invention 90 arise from the improved construction whereby it is possible to locate the atmospheric well entirely within the carbureting passage while maintaining all of the advantages of removability.

Further advantages arise from the improved means for holding the disks in position within the fuel feeding devices.

I claim:

1. In a carburetor, a main body having an air passage therein forming a mixing chamber extending completely through the body in one direction, a base secured to said body and having a fuel passage therein, said base closing the through extension of said passage, a float chamber exteriorly of the mixing chamber and communicating with said fuel passage, an atmospheric well physically inside of the walls of the mixing chamber and communicating with said fuel passage, and means for delivering fuel from said well to said mixing chamber, said well being bodily removable from said base.

2. In a carburetor, a main body having an air passage therein forming a mixing chamber extending completely through the body in one direction, a base secured to said body and having a fuel passage therein, said base closing the through extension of said passage, a float chamber exteriorly of the mixing chamber and communicating with said fuel passage, an atmospheric well physically inside of the walls of the mixing chamber and communicating with said fuel passage, and means disposed laterally of said well and carried by said base for delivering fuel from said well to said mixing chamber, both said well and said means being bodily removable from said base.

3. In a carburetor, a main body having an air passage therein forming a mixing cham-

ber extending completely through the body in one direction, a base secured to said body and closing the through extension of said passage, an atmospheric well carried by said base and located physically inside of the walls of said mixing chamber, fuel feeding means within said mixing chamber carried by said base and disposed laterally of said well, said means being operatively connected to said well, and a separate fuel supply for said means, said well and said means both being removable from said base.

4. In a carburetor, a main body having an air passage therein forming a mixing chamber extending completely through the body in one direction, a base secured to said body and closing the through extension of said passage, an atmospheric wall carried by said base and located physically inside of the walls of said mixing chamber, fuel feeding means within said mixing chamber carried by said base and disposed laterally of said well, said means being operatively connected to said well, and a separate fuel supply for said means, said well and said means both being removable from said base and said operative connection between said well and said means being freely accessible upon and by removal of said well and means.

5. In a carburetor, a main body having an air passage therein forming a mixing chamber extending completely through the body in one direction, a base secured to said body and closing the through extension of said air passage, a removable atmospheric well carried by said base and located physically inside of the walls of said passage, a fuel feeding means within said passage positioned laterally of said atmospheric well, said fuel feeding means being operatively connected to said well, means operative for feeding a substantially constant supply of fuel per unit of time to said well when free of accumulated fuel irrespective of engine suction, and separate fuel feeding means cooperating with said well and discharging into said passage.

In testimony whereof I have hereunto set my hand.

VICTOR R. HEFTLER.
